BOUNCING ATTACHMENT FOR SHOES

Philip N. Youtz, Yorktown Heights, N. Y.

Application November 30, 1955, Serial No. 550,102

3 Claims. (Cl. 36—7.8)

This invention relates to a bouncing attachment for 15 shoes and has for its object to provide a novel device which can be permanently or detachably secured to the bottom of a shoe and which will give the wearer of the shoe a bouncing effect when he is either walking or running, thereby enabling him to increase the length of his stride without making any increased exertion.

The bouncing attachment herein shown is in the nature of a gas inflated body of elastic material adapted to be secured to the bottom of a shoe.

When a person having shoes equipped with the bouncing attachment is walking or is running, the body of each attachment yields when it is brought into contact with the ground and carries the weight of the wearer, with the result that the gas in the body is compressed. As the wearer starts to raise his foot from the ground for the next stride, the compressed gas in the body expands and tends to lift the foot upwards and forwards, thus enabling the wear to increase his stride without making any additional effort.

The compressing of the gas in each body when it is brought into contact with the ground does not involve any extra exertion on the part of the wear as such compression is caused by the weight and momentum of the wearer, but the energy stored up in the compressed gas is released as the foot of the wearer is about to be lifted from the ground and is expended in increasing the length of the stride of the wear, as stated above.

In order to give an understanding of the invention, I have illustrated in the drawings some selected embodiments thereof which will now be described.

In the drawings:

Fig. 1 is a side view of a shoe equipped with my improved bouncing attachment;

Fig. 2 is a section on the line 2—2, Fig. 1;

Fig. 3 is a section on the line 3—3, Fig. 1;

Fig. 4 is a plan view of the bouncer device, the shoe to which it is attached being shown in dotted lines;

Fig. 5 illustrates an endless inflated tube which can be used in making the body member of the device shown in Figs. 1, 2, and 3;

Fig. 6 is a side view of a modified form of the invention;

Fig. 7 is a bottom plan view of Fig. 6.

In the drawings, 1 indicates a shoe which may be of any suitable or usual construction, and 2 indicates generally the bouncing device embodying the invention which is attached to the shoe.

The bouncing device includes a gas inflated body 3 of elastic material, such for instance as rubber or the rubber-like material of which pneumatic tires are commonly made. Any suitable gas may be used for inflating the body 3, but it will probably be most convenient to use air for this purpose.

The bouncing device, when attached to a shoe, is designed to provide a tread portion that is larger in area than the heel and sole of the shoe to which it is attached so as to reduce the number of pounds per square inch

on that portion of the tread which contacts with the ground. The effect of this reduction in pounds per square inch will be to absorb shock and cushion the wearer's feet in much the same manner as a balloon tire absorbs shock and cushions the wheels of an automobile.

5 The body member 3 of the bouncing device is large enough to confine a considerable volume of air and has walls of sufficient area to easily stretch, thus bringing into play the elasticity of both the air and the rubber or rubber-like substance of the walls of the body member.

The body 3 of the bouncing device is preferably made with a plurality of longitudinally extending interior chambers which have communication with each other on each end of the body, the adjacent chambers being separated by a vertical partition which extends from the top to the bottom of the body. The chambers are preferably of substantially the same size, and this feature together with the partition serves to balance the shoe of the wearer and prevent it from tilting to one side or the other when 10 the device is being used. Two preferred designs intended to give the shoe a solid base are hereinafter described and illustrated in the drawings, but it is to be understood that the interior chambers of the body may have other arrangements than those illustrated in the drawings without departing from the invention.

In the construction shown in Figs. 1—4 the body member 3 has two interior chambers 4, each extending longitudinally of the body and arranged side by side, said chambers being separated by a vertically extending partition 6. The chambers are so constructed that they communicate with each other at each end of the body. The body 3 may be inflated through a suitable valve device 5 of any usual or desirable construction.

One way of making the body 3 which is illustrated in Figs. 1—4, is first to provide an endless along tubular member 8 of elastic material as shown in Fig. 5, and then to bring the two inner side walls 30 of said member into contact with each other and vulcanize them together, thereby to produce the vertical partition 6 as indicated in dotted lines, Fig. 5. The body member thus produced has the two elongated chambers 4 which communicate with each other at each end of the body.

The body 3 may, if desired, have a shoe-positioning element mounted thereon to assist in maintaining the proper relation between a shoe and the body when the latter is attached to the shoe. The shoe-positioning member herein illustrated is indicated at 34 and it comprises a supporting portion 35 adapted to receive the sole 14 of the shoe 1 to which the device is to be attached, said 20 support portion 35 having at each side thereof an upstanding positioning rib 36 which rises thereabove, said ribs 36 providing between them a space to receive the sole of the shoe.

The shoe-positioning member 34 is preferably permanently secured to the top of the body member 3, and this may be accomplished by cementing or vulcanizing said support member to said body.

The support portion may be made of a length corresponding to that of the shoe so that not only the sole 14 of the shoe but the heel thereof will rest on said support portion. The positioning ribs 36 may extend clear around the peripheral portion of the support portion 35, in which case one section of said rib will enclose the heel of the shoe and another section of said rib will enclose the toe of the shoe. If so desired, the shoe-positioning member might be made of a length less than the length of the shoe, in which case the positioning rib 36 might not extend around the heel and toe portion of the shoe. In either case the shoe-positioning member serves to maintain the proper position of the body member relative to the shoe to which it is attached.

The body member may be either permanently or de-

tachably secured to the shoe. In the drawings I have shown a construction by which the body member is detachably secured to the shoe so that it can be attached to the shoe when it is desired to use it and can be removed from the shoe when the occasion for its use has terminated.

In the construction herein illustrated, the body member is provided with two attaching members 10 which are preferably permanently secured to the upper portion of the side walls of the body member and each of which extends above the body member and is provided with lacing openings 11 on its upper edge that are adapted to register with some of the lacing openings 12 with which the shoe is provided. The attaching members 10 are shown as being provided with attaching fingers 13 which overlie the side walls of the body member and which are vulcanized or otherwise permanently secured thereto.

In attaching the bouncer device to a shoe the shoe-positioning member 34 is brought into engagement with the sole 14 of the shoe with said sole occupying the space between the positioning ribs 36 and the attaching members are brought over the top of the shoe so as to place the openings 11 therein in register with the lacing openings 12 of the shoe, and then when the shoe is laced up 20 the lacing 15 will extend through the openings in both the shoe and the attaching members 10, and thereby the body is securely fastened to the shoe.

In order to assist in holding the device on the bottom of the shoe, I may provide said body with a hood member 16 at the toe portion thereof into which the toe 17 of the shoe may be inserted. This hood member 16 may be made of rubber or any suitable material and it is shown as having attaching arms 18 which overlie the sides and front of the body and are permanently secured thereto in any suitable way.

I may also provide a heel strap 19 which is permanently secured to the body and which assists in holding the heel portion of the body in proper position. The bottom or tread surface of the body may be reinforced if necessary or may even have a light weight tread member 20 secured thereto.

In Fig. 6 I have illustrated a different form of body which is made in two sections, a front section 21 and a heel section 22, each section being a gas inflated member. The front section 21 may be made in the same manner as shown with respect to the body illustrated in Figs. 1, 2, and 3, that is, it may be made so as to provide a central vertical partition 23 which extends lengthwise of the section 21 but not the full length thereof.

The two sections 21 and 22 are preferably permanently united together along the walls thereof that contact with each as shown at 24, and this union can be provided by vulcanizing the two sections together. Where the body is made in two sections, each section will have its air 55 valve 5 for inflating it. The device shown in Figs. 6 and 7 may be attached to the shoe by the same means illustrated in Figs. 1, 2, and 3.

When a person wearing the bouncer element is walking or running, the weight and momentum of the wearer 60 causes the gas in each body to be compressed when the

bouncer is brought against the ground, and as the wearer completes each stride and is about to lift his foot from the ground or supporting surface the energy stored up in the compressed gas is released and serves to propel the wearer forward, thus enabling him to increase his stride. The compression of the gas in each bouncing element does not involve any effort on the part of the wearer other than that normally exerted in walking or running, and the release of the energy stored up in the compressed gas at each stride imparts to the wearer a forward propelling force so that at whatever speed the wearer is walking or running the use of my improved bouncing elements enables him to increase his speed without increasing in any way the exertion involved in the walking or running operation.

I claim:

1. A bouncing attachment for shoes comprising a gas inflated body composed of an endless tube of elastic material having two elongated straight portions lying side by side and parallel to each other and extending lengthwise of the body, the adjacent side walls of said elongated portions being secured together to present a vertical partition extending from the top to the bottom of the body, whereby the body presents two elongated longitudinally extending chambers which have communication with each other at each end of the body, a shoe-positioning element on the top of the body and secured thereto, and means to attach said body to the bottom of a wearer's shoe.

2. A bouncing attachment for shoes comprising a gas inflated body of elastic material, which body presents a front section and a rear section connected together, each section having a separate gas receiving chamber, means by which each chamber can be inflated, and means for securing said body to a shoe beneath and in engagement with the sole thereof.

3. A bouncing attachment for shoes comprising a gas inflated body composed of an endless tube of elastic material having two elongated straight portions lying side by side and parallel to each other and extending lengthwise of the body, the adjacent side walls of said elongated portions being secured together to present a vertical partition extending from the top to the bottom of the body, whereby the body presents two elongated longitudinally extending chambers which have communication with each other at each end of the body, a shoe positioning element separate from the body and resting thereon and secured thereto, said shoe positioning element having an upstanding peripheral rib which encloses a space to receive the sole of the wear's shoe, and means to attach the body to the shoe with the sole thereof resting on the shoe-positioning element.
